Patented Aug. 8, 1916.

UNITED STATES PATENT OFFICE.

PALMER O. POULSON, OF ROSWELL, NEW MEXICO.

INSOLE.

1,193,608.

Specification of Letters Patent. Patented Aug. 8, 1916.

Application filed October 26, 1915. Serial No. 57,993.

To all whom it may concern:

Be it known that I, PALMER O. POULSON, a citizen of the United States of America, residing at Roswell, in the county of Chaves 5 and State of New Mexico, have invented certain new and useful Improvements in Insoles, of which the following is a specification, reference being had therein to the accompanying drawing.

10 This invention relates to in-soles for shoes and has for its object the production of a simple and efficient in-sole which may be quickly and efficiently applied to a shoe and constitute a yieldable cushion support for 15 the foot.

A still further object of this invention is the production of a pneumatic in-sole, so arranged as to constitute a cushion support for the foot, under the heel and toe of the 20 foot, the portion of the in-sole being flat which extends under the toes of the foot.

With these and other objects in view, this invention consists of certain novel combinations, constructions, and arrangements of 25 parts as will be hereinafter fully described and claimed.

In the accompanying drawing: Figure 1 is a longitudinal section of a shoe, showing the cushion applied thereto. Fig. 2 is a 30 plan view of the inner portion of the cushion, the outer casing being removed therefrom. Fig. 3 is a plan view of an embodiment or modified form of the invention. Fig. 4 is a section taken on line 4—4 of Fig. 3. Fig. 5 is a section taken on line 5—5 of Fig. 3. Fig. 6 is a section taken on line 6—6 of Fig. 3.

Referring to the accompanying drawing by numerals it will be seen that 1 designates 40 the shoe within which the in-sole is placed. The in-sole comprises an outer covering 2 which is preferably fitted snugly over the inner rubber tube 3 and held upon the outer face thereof by means of any suitable adhesive material. The rubber tube 3 comprises the upper section 4 and the lower section 5, which sections are cemented closely together around the periphery thereof as shown by the numeral 6 in Fig. 2, and the sections 4 and 5 are cemented together along 45 a line indicated by the numeral 7 in Fig. 2 for producing a flat toe-engaging face 8

upon the outer or forward end of the in-sole. It will therefore be seen that a pneumatic cushion is produced by forcing air between 55 the upper and lower portions 4 and 5 of the in-sole and after the air is forced therebetween, the edge of the in-sole may be sealed at the point of entrance of the air. It will be seen that the pneumatic tread 9 will constitute a very efficient pneumatic cushion for 60 the heel and ball of the foot, thereby producing an easy tread.

In Figs. 3 to 6 inclusive, there is shown a slight embodiment of the invention where- 65 in the lower portion 10 and the upper portion 11 are cemented together around the periphery thereof and also cemented together upon the adjacent faces for leaving an oval pocket 12 near the forward end of 70 the in-sole for engagement by the ball of the foot and also an oval pocket 13 near the rear of the in-sole for supporting the heel of the foot. A substantially crescent-shaped pocket 14 is employed near the inner 75 central edge of the in-sole and is adapted to be inflated, the pockets 12 and 13 being connected to the crescent-shaped pocket 14 by means of the passageway 15. A projecting tube 16 communicates with the crescent- 80 shaped pocket 14 for facilitating the inflation of the pockets 12, 13 and 14, and this tube 16 may be bent backwardly as indicated in dotted lines in Fig. 5 and may extend under the in-sole for preventing the escape- 85 of air from the tube 16.

From the foregoing description, it will be seen that a very simple and efficient pneumatic in-sole has been produced for constituting a soft detachable tread to be 90 applied within a shoe. It should be understood that the upper and lower portions 10 and 11 may be covered by means of a fabric lining or cover when so desired, such as is illustrated in Fig. 1.

95 What I claim is:—

As a new article of manufacture, an in-sole comprising an outer casing, an inner cushion positioned within said outer cas- 100 ing, said inner cushion provided with a substantially crescent shaped pocket near one side thereof and adapted to extend under the arch of the foot of the wearer, said inner cushion also provided with an oval

5 pocket near the rear end of said in-sole to extend under the heel of the wearer, said inner casing also provided with a forward pocket adapted to extend under the ball of the foot of the wearer, said in-sole provided with passageways forming a communication between said crescent shape pocket and both

of said other pockets, and a filling tube communicating with said crescent shape pocket whereby the pockets in said in-sole may be 10 inflated when so desired.

In testimony whereof I hereunto affix my signature.

PALMER O. POULSON.
